UNITED STATES PATENT OFFICE.

FREDERICK INKE, OF SAN FRANCISCO, CALIFORNIA.

LOSS-PROOF POCKET.

1,123,539.

Specification of Letters Patent.

Patented Jan. 5, 1915.

Application filed October 27, 1913. Serial No. 797,506.

To all whom it may concern:

Be it known that I, FREDERICK INKE, a citizen of Russia, residing at San Francisco, in the county of San Francisco and State of California, have invented certain new and useful Improvements in Loss-Proof Pockets, of which the following is a specification.

My invention relates to loss-proof pockets for garments and the primary object is to provide an auxiliary pocket in an ordinary pocket of a garment which prevents the loss of coins or articles held in the pocket and the removal of the contents by pickpockets.

Another object of my invention is to provide means for removably securing an auxiliary pocket in an ordinary pocket of a garment.

Another object of my invention is to provide means attached to the auxiliary pocket for preserving the shape of the latter.

Other objects as well as the nature and characteristic features and scope of my invention will be more readily understood from the following description taken in connection with the accompanying drawing and appended claims.

In the drawings: Figure 1, represents a front elevational view of a pocket showing the same partly broken away and my invention attached to the inner side of the same. Fig. 2, is a vertical sectional view of my invention applied to the pocket of a garment. Fig. 3, is a fragmentary front elevation of my invention showing the same in open position.

Referring more particularly to the drawings, the numeral 1, represents a fragment of a garment having secured thereto an ordinary pocket 2. Intermediate the ends of the pocket 2 and detachably secured to the garment 1, through the medium of buttons and button holes or the like fastening devices 3, is my auxiliary loss-proof pocket 4.

The auxiliary pocket 4 comprises a piece of material, preferably cloth, cut and folded upon itself at its lower portion to provide rear and front walls 5 and 6, the edges of which diverge downwardly, the space formed between the sides of the two pockets 50 constituting a recess for receiving a pencil or the like. The outer edges of the rear wall 5 and the front wall 6 are secured together in any suitable manner. For the purpose of preserving the shape of the pocket 4, I have secured to the upper outer edge of the front wall 6, a stiffening strip 7, the

latter having its side edges arranged in alinement with the side edges of the front wall. It can be seen from Fig. 2, of the drawings that the bottom of the pocket 4, is slightly spaced from the bottom of the ordinary pocket 2, which allows the pocket 4 to stretch and not unnecessarily bulge the pocket 2, when the former contains articles. The upper portion 65 of the material 5 is folded upon itself slightly above the line of securement to the garment 1 and is stitched transversely across adjacent its upper end to the upper end of the rear wall as clearly shown in Figs. 1 70 and 2, of the drawing, for strengthening purposes, and the double thickness is removably secured to the garment 1, preferably by means of buttons and button holes or the like fastening devices 8, the latter being arranged alternately across the pocket upon opposite sides of the transversely extending stitches. The portion depending therefrom has its extreme outer end tapered and constitutes a flap or cover 9 for the pocket 4. 80 The flap 9, is held from entering the pocket by the upper end of the stiffening strip 7.

For the purpose of closing the pocket I have provided the inner face of the flap 9 with a socket 10 adapted to engage a head 85 11, upon the outer face of the stiffening strip 7. It is obvious that other fastening devices may be used for securing the flap to the stiffening strip.

It will be obvious to those skilled in the art to which this invention relates that modifications may be made in detail without departing from the spirit or scope of the invention.

Having thus fully described my invention 95 what I claim as new and desire to secure by Letters Patent is:

1. An auxiliary pocket comprising a piece of material having the lower portion thereof cut and folded upon itself to provide front 100 and rear walls, said walls having their outer edges secured together to provide a pocket, a stiffening strip secured to the upper outer surface of the front wall, said stiffening strip having the side edges thereof arranged 105 in alinement with the side edges of the front wall, the upper portion of the material being folded upon itself to provide a flap for closing the pocket, stitches extending transversely across the upper part of the flap 110 securing the flap and rear wall for strengthening purposes, means for removably fas-

tening said flap to said strip, the double thickness of the upper portion of the material being provided with button holes for facilitating the securing of the material to a garment pocket, and said rear wall being provided with button holes arranged below said stitches and alternately with said first mentioned button holes for facilitating the safety securing of the auxiliary pocket to a garment pocket.

2. In combination with a pocket of a garment, an auxiliary pocket of less width removably secured to the inner side of said

garment pocket, the side edges of said auxiliary pocket being arranged in downward diverged relation with each other, and the space between the sides of said pockets constituting a recess for the reception of a pencil or the like. 15

In testimony whereof I affix my signature 20 in presence of two witnesses.

FREDERICK INKE.
